UNITED STATES PATENT OFFICE.

BICKLEY W. CLOAK, OF DAYTON, OHIO, ASSIGNOR OF ONE-HALF TO JOHN CLOAK, OF SAME PLACE.

CAR-COUPING.

SPECIFICATION forming part of Letters Patent No. 274,908, dated April 3, 1883.

Application filed November 20, 1882. (No model.)

To all whom it may concern:

Be it known that I, BICKLEY W. CLOAK, a citizen of the United States, residing at Dayton, in the county of Montgomery and State of Ohio, have invented a certain new and useful Improvement in Car-Coupling Chains; and I do hereby declare that the following is a full, clear, and exact description of the invention, which will enable others skilled in the art to which it appertains to make and use the same, reference being had to the accompanying drawings, and to the letters of reference marked thereon, which form a part of this specification.

15 My invention relates to a chain adapted to couple cars when the drag-bar is broken or displaced; and it consists of two chains, on the free ends of which are hooks, and the other ends are attached to the ordinary coupling-link.

The mechanism is illustrated in the accompanying drawing, which is a side view of the cars as coupled with the improved chain.

At A is represented in section an ordinary box-car, the division being immediately outside of the inner truss-rods.

F is one of the central longitudinal sills, and into which are framed two transverse sills, near the end of the car.

30 E is one of the inner truss-rods, that extend the full length of the car-body.

D is the coupling-chain, to the free ends of which are attached hooks, the other ends being attached to an ordinary coupling-link.

35 To the car B is attached the ordinary drag-bar, C, of which the car A has been deprived, and when such is the case it becomes necessary to use a chain to effect the coupling.

By my invention the coupling is effected by attaching the hooks to the truss-rods of the 40 car deprived of the drag-bar and securing the link of the chain within the drag-bar of the opposite car by the ordinary pin. Thus coupled, the draft in the damaged car is on the truss-rods and the end sill.

45 This coupling is secure and much more convenient than as ordinarily done by means of a long chain around the truck-frame.

Having fully described my invention, what I claim, and desire to secure by Letters Patent, is—

1. In a chain for coupling cars, the chain provided at about the middle of its length with a ring, within which is held a coupling-link, the two ends of the chain being provided with hooks, by which it can be secured to the truss-rod of a car, it being coupled to another car by the link, said chain being adapted to form a coupling when other means have become broken or detached, substantially as described.

2. The car-coupling chain D, having a central connecting-link and two free ends, in combination with the truss-rod of a car and the draw-head of another car, substantially as set forth.

In testimony that I claim the foregoing as my own I affix my signature in presence of two witnesses.

BICKLEY W. CLOAK.
